WALL REGISTER

James W. Bergstrom, Harrison, Wis., assignor to
 Bergstrom Manufacturing Company, Neenah,
 Wis., a corporation of Wisconsin

Application May 15, 1934, Serial No. 725,812

4 Claims. (Cl. 98—108)

This invention relates to a wall register, the general object of the invention being to so form the head or fitting that a uniform flow of air is secured from the register, and to provide means whereby a tight fit is provided between the walls of the register receiving opening and the adjacent parts of the register to prevent air leaks at this point, which tends to mark the wall of the room adjacent the opening.

10 This invention also consists in certain other features of construction and in the combination and arrangement of the several parts, to be hereinafter fully described, illustrated in the accompanying drawing and specifically pointed out 15 in the appended claims.

In describing the invention in detail, reference will be had to the accompanying drawing wherein like characters denote like or corresponding parts throughout the several views, and in which:

20 Figure 1 is a front view of the register, with part of the grille broken away.

Figure 2 is a section on line 2—2 of Figure 1.

In this drawing, the letter A indicates a portion of the walls of rooms of a building, and the letter B the floors thereof and the letter C indicates a vertical passage or conduit having openings therein opening out into the rooms so that heated air can be conveyed from a heating system or the like to the rooms. The register head or fitting is shown at D and may be provided with the double walls 1 to provide an air space between the two walls 1, as shown in Figure 2, or the head or fitting may be provided with but a single wall. The rear wall of the head or fitting has a lower part 2

35 which slopes upwardly and toward the register opening from its point of connection with the conduit 3 and said wall is formed with a substantially horizontally arranged short part 4 at the upper end of the part 2 and from the front 40 end of this short part 4 the said wall slopes upwardly and inwardly toward the register opening, as shown at 5, where it joins the flange 6 which fits in the register opening. This part 5 may be formed with the projections 7, each of 45 which is of substantially L-shape, with its short limb lowermost, as shown in Figure 2. The lower front wall of the head or fitting slopes upwardly and toward the register opening, as shown at 8, from its point of connection with the conduit 3

50 to the point where it joins the flange 6. The outer edge of the flange 6 joins a vertical flange 9 which contacts the plaster 10 of the wall A, with said plaster engaging the flange 6, as shown in Figure 2, so that a substantially air-tight joint 55 is formed between the plaster and the head or

fitting, where the head or fitting passes through the register opening in the wall.

A damper 11 is placed in the head or fitting and is hinged preferably to the lower part of the portion 2 of the rear wall of the head or fitting, as shown at 13, and this damper may be controlled from the room in any suitable manner, it, of course, being understood that when the damper is closed, it extends across the lower part of the head or fitting and rests on a part of the 10 wall 8.

The grille for closing the discharge end of the head or fitting is shown at 14, and is held in position in any suitable manner.

Thus it will be seen that the peculiar shape of 15 the head or fitting provides a uniform discharge of air into the room as the projections 4 and 7 and the upwardly and forwardly sloping rear parts 2 and 5 direct the air toward the opening and the forwardly and upwardly sloping part 8 permits the air to escape from the lower part of the opening without being checked so that the air passes from the lower part of the opening with practically the same velocity as it passes from the rest of the opening. When the damper 11 is partly 25 closed, the device will maintain a practically equal flow of air at all points of the opening, but with a greater velocity at the bottom of the opening, where it is most desirable, especially in a head or fitting located in the baseboard or just 30 above the baseboard.

With this invention, dead spots at the register opening are eliminated and there is no intake of air as in the heads or fittings as now made.

The flanges 6 and 9 act as a plaster ground as 35 well as connecting joints between the register face and head and permits a packing of any suitable material between the register face and head so as to prevent leakage of air, which causes dirty 40 and streaky walls.

This head or fitting may be constructed for use on any system where the flow of air is an important item and its most common use at the present time would be on hot air heating, both gravity and forced air, and indirect steam vapor 45 or hot water systems, though its use may not necessarily be confined to heating plants or systems.

In a fitting having an opening 8 inches high 50 and 12 inches long and of the construction now in use, tests have proven that there is no flow of air at the bottom of the opening and for a distance of about 3 inches above the bottom. In other words, only about two-thirds of the head 55

is efficient and about this same ratio holds true regardless of size.

Further, the tests show the air at the bottom part of the opening is very apt to be drawn in the head or fitting, thus causing a retarding of the air being discharged and also a cooling of this discharged air because the air taken in is colder than the air discharged.

Thus it will be seen that I have provided means for diverting the air travel so as to secure a uniform flow of air through the register opening, while preventing air from the room entering the register and retarding the flow of hot air into the room, with means for preventing leakage of air between the head and the walls of the opening, which causes disfiguration of the walls of the room.

While the device is shown and described used with an opening in a vertical wall, it is to be understood that the device can be used with openings otherwise located and it is also to be understood that the baffles formed by the parts 2, 4, 5 and 7 can be formed separately or together and suitably attached to the rear wall of the head and that any number of these baffles may be used, as the number used and their sizes will depend on the size of the register openings. Furthermore, the rear part of the head may be of any shape desired and the baffle forming parts be arranged to cause the heated air to pass from the register in a uniform manner.

It is thought from the foregoing description that the advantages and novel features of the invention will be readily apparent.

It is to be understood that changes may be made in the construction and in the combination and arrangement of the several parts, provided that such changes fall within the scope of the appended claims.

What is claimed is:

1. A register device comprising a part having an opening, a conduit, and means for directing air from the conduit through the opening to provide

an equal flow of air through all parts of the opening, such means comprising a head having its rear wall sloping upwardly from the rear wall of the conduit to the upper end of the opening, a front wall sloping from the front wall of the conduit to the lower end of the opening, said rear wall having a forwardly extending projection thereon, the lower end of which is substantially horizontally arranged and extends forwardly from the rear wall.

2. In a register device including a member having a discharge opening therein and a conduit, a head having a rear wall sloping upwardly and forwardly from the rear wall of the conduit to the upper end of the opening, said rear wall having an offset portion intermediate its ends forming a horizontal, forwardly extending shoulder, and said head having a front wall sloping upwardly and forwardly from the front wall of the conduit to the lower end of the opening.

3. In a register device including a member having a discharge opening therein and a conduit, a head having a rear wall sloping upwardly and forwardly from the rear wall of the conduit to the upper end of the opening, said rear wall having an offset portion intermediate its ends forming a horizontal, forwardly extending shoulder, said head having a front wall sloping upwardly and forwardly from the front wall of the conduit to the lower end of the opening, said rear wall, above the shoulder forming portion, having forwardly extending projections provided with horizontal lower ends.

4. In a register device including a member having a discharge opening therein and a conduit, a head having a rear wall sloping upwardly and forwardly from the rear wall of the conduit to the upper end of the opening, said rear wall being formed in step-like formation to provide lower horizontal portions and vertically inclined portions rising therefrom thereby providing forwardly extending projections.

JAMES W. BERGSTROM.
